UNITED STATES PATENT OFFICE

SEAWELL C. NORMAN, OF GOLDSBORO, NORTH CAROLINA

AUTOMATIC VENEER TABLE

Application filed December 1, 1930. Serial No. 499,344.

- This invention appertains to new and useful improvements in veneer tables, and more particularly to a table from which veneer can be transferred in a quick and efficient manner.
- 5 The principal object of this invention is to provide a veneer table from which the veneer can be transferred automatically without interruption to the operation of the veneer cutting machinery.
- 10 These and other important objects and advantages of the invention will be found in the following specification.
- In the drawings:—
- Figure 1 represents a side elevational view 15 of the novel table structure and associated machinery showing the conveyor for the supply of logs.
- Fig. 2 represents a fragmentary top plan view of the veneer table and diagrammatically showing the electrical control.
- Fig. 3 represents a sectional view taken substantially on the line 3—3 of Fig. 2.
- Fig. 4. represents a sectional view taken substantially on the line 4—4 of Fig. 3.
- 25 Fig. 5 represents a sectional view taken substantially on the line 5—5 of Fig. 2.
- Fig. 6 represents a fragmentary detailed sectional view of the automatic switch means showing the stationary and mobile elements thereof in opposed spaced relation.
- 30 Fig. 7 represents a fragmentary detailed sectional view of the switch means showing the stationary and mobile elements thereof in opposed spaced relation.
- 35 Referring to the drawings wherein like numerals designate like parts, it can be seen that numeral 5 represents the trackway made up of a pair of rails upon which the table generally referred by numerals 6 rides. This table 6 is made up of a frame 7 of rectangular shape, across which the axles 8 extend. At each end of each of the axles 8 is a flanged or grooved wheel 9, for riding contact with its corresponding rail of the trackway 5.
- 40 An elongated rack bar 10 has its ends 11 bent inwardly as shown for connection to the frame 7 and meshing with this rack bar 10 is the pinion 12 on the armature bar 13 of the motor 14.
- 45 Any suitable manual switch means can be
- employed for controlling the motor in its reversed direction. Beyond the shafts 8 are shafts 15, one of which is equipped with a beveled gear 16 at one end meshing with the beveled gear 17 on the shaft of a second motor 18. Each of these shafts 15 is equipped with sprocket wheels 19 and over the corresponding sprocket wheels of the shaft 15 are trained chains 20, upon which the sheet 21 lays as it is cut from the log 22, mounted 55 upon the shaft 23.
- 55 Numeral 29 represents the cutter blade for cutting the veneer. As is clearly shown in Fig. 1, numeral 25 represents the beam along with the block 26 and rollers 27 are movable. A chain 28 is suspended by the block 26 and carries tongues 29 for supporting a log 30, ready to replace the preceding log 22.
- 60 Fig. 1 shows a receiving table for receiving the veneer 21 from the table 6 and to accomplish this, switch means generally referred to by numeral 32 is provided. This switch means provides a contact 33 of triangular shape on the frame 7 and a V-shaped receiving contact 34 on the table 31. The contact 33 connects to the motor 18 inside of the circuit 35, while the contact 34 represents the switching side of the circuit, which is made up of the switches 36 and 37, the former 65 being located adjacent the table 6 and the latter adjacent the table 31 which can be operated by the attendant.
- 65 Fig. 1 shows a receiving table for receiving the veneer 21 from the table 6 and to accomplish this, switch means generally referred to by numeral 32 is provided. This switch means provides a contact 33 of triangular shape on the frame 7 and a V-shaped receiving contact 34 on the table 31. The contact 33 connects to the motor 18 inside of the circuit 35, while the contact 34 represents the switching side of the circuit, which is made up of the switches 36 and 37, the former 70 being located adjacent the table 6 and the latter adjacent the table 31 which can be operated by the attendant.
- 70 Obviously, when the contacts 33 and 34 are engaging, the table 6 can be emptied by 75 the closing of either one of the switches 36 or 37, the same serving to energize the motor 18 and cause the operation of the chains 20 for discharging the veneer from the carriage or table 6 onto the table 31.
- 75 While the foregoing specification sets forth the invention in specific terms, it is to be understood that numerous changes in the shape, size and materials may be resorted to without departing from the spirit and scope 80 of the invention as claimed hereinafter.
- 85 Having thus described my invention, what I claim as new is:—
- 90 1. A veneer table comprising a track, a wheeled vehicle, a conveyor on the vehicle, a 95

motor for operating the conveyor, a stationary contact separate from the vehicle, the contact on the vehicle, a motor circuit including the contact, and a motor on the vehicle, said circuit including the contact and a switch in the circuit for closing the circuit when the contacts are engaged.

2. A veneer table comprising a trackway, a vehicle movable on the track, a motor for driving the vehicle reciprocatorily, a motor on the vehicle, a conveyor on the vehicle driven by the motor thereon, and remote switch means for energizing the motor on the vehicle to operate the conveyor when desired.
- 10 3. A veneer table comprising a trackway, a vehicle movable on the track, a motor for driving the vehicle reciprocatorily, a motor on the vehicle, a conveyor on the vehicle driven by the motor on the same, remote switch means for energizing the motor on the vehicle to operate the conveyor when desired, and a limit switch associated with the vehicle for supplementing the action of the remote switch means in energizing the motor.
- 15 20 25

In testimony whereof I affix my signature.
SEAWELL C. NORMAN.
